UNITED STATES PATENT OFFICE.

WILLIAM PHILIPSON, THOMAS WHITTLE HOPWOOD PHILIPSON, AND PERCY CLARKSON PHILIPSON, OF BOLTON, ENGLAND.

EXPANSIBLE PULLEY.

1,112,345.

Specification of Letters Patent. Patented Sept. 29, 1914.

Application filed August 23, 1912. Serial No. 716,716.

To all whom it may concern:

Be it known that we, WILLIAM PHILIPSON, THOMAS WHITTLE HOPWOOD PHILIPSON, and PERCY CLARKSON PHILIPSON, subjects of the 5 King of Great Britain, and residents of Holland Street Works, Astley Bridge, Bolton, in the county of Lancaster, England, have invented a certain new and useful Improvement in Expansible Pulleys, of which 10 the following description, together with the accompanying sheets of drawings, is a specification.

This invention relates to expansible pulleys of the type advantageously employed in 15 connection with the driving gear of a motor road vehicle, especially when such motor vehicles are of the type known as motorcycles, motor-tricycles, or the like, wherein a flexible driving belt is employed. In connection 20 with this type of driving gear the driving belt is propelled by the employment of two disks mounted upon one and the same shaft with their opposed surfaces inclined to each other or of such formation as will enable the use of the flexible driving 25 belt of tapering form in cross section, and the object of our invention is a novel means of adjusting these disks in position relatively with each other to vary the interval 30 between so that when said disks are in position nearest to each other the driving belt engages same nearest their peripheries at which time the speed of such driving belt will be at its maximum while when said 35 disks are separated to the greatest extent the driving belt will approach nearest to the center of their rotation and therefore the speed of such belt will be at its minimum. Many devices have been employed for this 40 purpose but most of them are of complicated character, whereas by the employment of our devices such complicated parts are eliminated and few operative parts of comparatively simple construction are substituted.

45 In the accompanying sheets of drawings which are illustrative of our invention:— Figure 1 is a diametrical section of our improved device as arranged in conjunction with the bevel faced driving disk for transmitting motion to parts well understood, said disks being shown in close proximity to

each other. Fig. 2 is a view showing most of the parts in elevation but with a part (hereinafter described as a spring box) broken away, the bevel faced driving disks 55 in this case being shown at their greatest distance apart. Fig. 3 is an end elevation of the parts shown by Figs. 1 and 2 as seen in the direction indicated by the arrow *a*, with the end cover of the spring box and 60 other parts removed so that the spring and its connections may be more clearly seen. A brake device is also shown in connection with this arrangement of devices. Figs. 4 and 5 are side and end elevations respectively in detail of a device that is or may be employed for holding or locking the movable or screw-operated part in position as hereinafter described. Fig. 6 is a sectional elevation showing a modification of certain 70 of the parts shown by Figs. 1 and 2.

In the type of driving gear herein referred to and as illustrated by the accompanying sheets of drawings, the bevel faced driving disks *b* and *b*¹, transmit motion to 75 the appropriately shaped driving belt which acts in conjunction with them in manner well known, and on being moved closer together or farther apart move the said belt respectively at a faster or slower speed as 80 is well understood, and as the adjustment of these disks *b*, *b*¹ at a greater or less distance apart is the peculiar function of our mechanical device we have illustrated same in conjunction with these disks *b* and *b*¹. In 85 doing this it will be observed that the main driving shaft *c* has the disk *b*¹ securely fixed upon it and this disk *b*¹ has a sleeve 2 which extends beyond said shaft *c* so that we mount thereon the disk *b* which has a sleeve 90 3 embracing the sleeve 2 formed on the disk *b*¹. The sleeve 3 is provided with a key way to accommodate a key 4 secured to the sleeve 2, so that at all times the rotary motion of the shaft *c* as transmitted to the disk *b*¹, 95 will through the key 4 be transmitted to the disk *b*, while at the same time said disk *b* and its sleeve 3 may be slidably moved upon the sleeve 2 of the disk *b*¹. In other words, in addition to the rotary motion that is 100 transmitted to the disk *b* said disk *b* may be moved lengthwise of the shaft *c*.

On the outer end of the sleeve 3 are formed screw threads 6 which mesh with the screw threads 5, formed within the sleeve d^1 of a spring box d . This spring box d has mounted therein a spiral recoil spring f which has its outer end secured thereby engaging the notch f^1 as shown by Fig. 3, while its inner end engages over the hook g^1 of the hoop g . The hoop g embraces the outer end of the sleeve 2 and is retained thereon by the threaded sleeve h^1 of the nut h which forces the projection h^1 of the washer h into the notches g^2 in said hoop g so that the rotary motion of the shaft c is transmitted through the disk b^1 and its sleeve 2 to this hoop g continuously. The plate k may also be rotated to adjust the tension of the spring f .

Upon the peripheral surface of the spring box d a suitable brake lever or band m is made to apply so that the user may by manipulating the pedal end of said brake lever m force said brake into contact with the periphery of said spring box d against the tension while the spring n will normally keep said brake lever m clear of said box d .

The action of the foregoing parts is as follows: Assuming that the driving shaft c is being continuously driven and that it is desired to reduce the speed of the motion transmitted by the driving disks b , b^1 revolving with same, such reduction of speed can be effected by moving the disk b away from the disk b^1 as, say from the position shown by Fig. 1 toward the position shown by Fig. 2 and to effect this it is only necessary to retard the motion of the spring box d by pressing upon the brake lever m so that instead of said spring box being rotated at the same speed as are the disks b , b^1 , its rotary motion is retarded, and by this retardation the spring within the box d is wound up and at the same time the action of the screw threads 5 in the sleeve d^1 acting upon the screw threads 6 on the sleeve 3 moves said sleeve 3 and its disk b along the sleeve 2 whereby the disk b recedes from the disk b^1 as desired.

On releasing pressure upon the brake lever m the retracting spring n will remove same from contact with the spring box d and permit the recoil spring f to rotate said box d to cause its screw thread 5 to act upon the screw thread 6 and thereby move the sleeve 3 and the disk b back to their normal positions adjacent to the disk b^1 . Thus it will be seen that in addition to the ordinary rotary motion that is transmitted to the disk b from the shaft c said disk b has by the accelerated or retarded rotation of the spring box and screw motion transmitted to it lengthwise said shaft c .

Under some conditions it is desirable that the spring box d should be capable of being locked in any adjusted position relative to

the disk b . For such purpose an arm as k^2 is provided (see Fig. 4) extended from the washer k so that a detent k^3 may be mounted thereon to engage with ratchet teeth d^2 formed on the periphery of the spring box d . It will be seen that such ratchet will hold said spring box d in such position relatively with the disk b as may be found desirable. When the disks b and b^1 are so far separated as to permit the driving belt to engage upon the periphery of the sleeve 2, said sleeve may have a rotary annular collar z mounted thereon as shown by Fig. 6 free to move upon said sleeve 2 by which means although the disks b and b^1 and their respective sleeves may be continuously rotating, driving belt and the annular collar will remain stationary.

We claim:

1. An expandible pulley embodying opposed inclined disks, one of which is axially movable relative to the other; means to rotate said disks in unison; an independently rotatable part; means to retard the movement of the independently rotatable part; means to accelerate the movement of the independently movable part when the retarding means is released; and means whereby the retarded and accelerated movements of the movable part move the movable disk longitudinally.

2. An expandible pulley embodying opposed inclined disks mounted to rotate, one of said disks being movable in parallelism with the axis of rotation; a part rotatable independently of the disks; threaded connection between the independently rotatable part and the movable disk whereby a difference in rotation of the independently rotatable part causes a movement of the disk; manual means for retarding the movement of the independently rotatable part; and mechanical means for accelerating the movement of the independently rotatable part when the manual retarding means is released.

3. In an expandible pulley opposed inclined disks, one of which is movable in parallelism with the axis of rotation; a collar capable of normal rotation with the disks and of independent rotation relative thereto; means whereby independent rotation of the collar causes movement of the movable disk; a spring connected with the collar; manual means for retarding the collar and placing the spring under greater tension; and means to withdraw the retarding means to permit the spring to accelerate the movement of the collar.

4. In an expandible pulley opposed inclined disks, one of which is movable in parallelism with the axis of rotation; an independently movable part; connection between the independently movable part and the movable disk whereby movement of the

independently movable part causes movement of the disk; manual means for retarding the movement of the independently movable part; means for locking the independently movable part when so retarded; and means to accelerate the movement of the independently movable part when the locking and retarding means are released.

In testimony whereof we have signed our

names to this specification in the presence of 10 two subscribing witnesses.
